UNITED STATES PATENT OFFICE.

ACHILLE MACCHIONI AND ENRICO HOCKE, OF GENOA, ITALY.

LOCOMOTIVE.

Application filed May 24, 1921. Serial No. 472,304.

To all whom it may concern:

Be it known that we, ACHILLE MACCHIONI and ENRICO HOCKE, both subjects of the King of Italy, both residing at 31, Via XX 5 Settembre, Genoa, Italy, have invented certain new and useful Improvements in Locomotives, of which the following is a specification.

The present invention relates to improvements in locomotives and consists in the application thereto of internal combustion horizontal cylinder engines. The advantages resulting from the fitting of internal combustion engines consist in obtaining with 15 equal capacity much more power or in providing within the space available on a locomotive much more powerful engines than usual. The horizontal disposition of the cylinders permits of transmitting the energy 20 to the driving wheels of the locomotives through the medium of very simple transmission members.

From among the various types of engines capable of being used we have selected for 25 the purpose of the present description an engine with horizontal cylinders and opposed pistons i. e., having a single compression chamber. This type of engine in addition to the general advantages of horizontal 30 cylinder engines possesses other advantages which render this type particularly suitable for application to locomotives. Said advantages include the neutralizing of the vibration due to reciprocating masses, the possibility of the further simplification of the 35 drive from the pistons to the wheels and of dispensing with valves and their operating levers.

In the preferred form of engine of this 40 type i. e. with horizontal cylinders and opposed pistons the movements of the pistons are so arranged that the two pistons of one cylinder at the end of their stroke first open the exhaust ports and then the scavenging 45 ports.

The annexed drawing shows diagrammatically by way of example the application to a locomotive of an engine according to the present invention, and also shows particulars of the said engine.

In said drawing:—

Figure 1 represents a diagram in axial longitudinal section of the installation upon the locomotive of a motor provided with 55 three pairs of cylinders.

Figure 2 represents on a larger scale a

vertical section of the separate motor according to Figure 1, and exactly on the line C—C of Figures 3 and 4, along the axes of the central pairs of the cylinders.

Figures 3 and 4 represent vertical sections on the line A—A, Figure 2, and line B—B of Figure 2.

For the sake of clearness we have represented on Figure 1 the pistons 3₁ and 3₂ in similar stroke positions, and in Figure 2 the pistons 4₁ and 4₂ in analogous positions.

In the drawings, the reference numerals have been placed so as to correspond with the central pairs of the cylinders, but said numerals relate also to all the other pairs of the cylinders forming part of the motor, the number and the arrangement of said parts being variable.

As shown in Fig. 1, the two cylinders 1 and 2 of the said pair each contain two pistons 3¹, 3², 4¹, 4² the former of which 3¹, 3² are represented as at the inner end of their compression stroke while the latter 4₁, 4₂ are shown as at the outer end of their stroke (exhaust and scavenging stroke) the movement of the pistons being so arranged on reaching the end of their stroke that the pistons 3², 4² uncover the exhaust ports 5 first and then the pistons 3¹, 4¹ uncover the scavenging ports 6.

The scavenging ports of the two cylinders 1 and 2 may be connected together by a chamber embracing the two cylinders and into which enters the inlet pipe for scavenging air; or the scavenging ports of the one cylinder may be completely separate from those of the other cylinders and may be supplied with scavenging air by two separate pipes or by branch pipes; the same arrangement may be applied to the exhaust ports.

In Figures 2, 3 and 4, we show the exhaust ports 5 of the upper cylinders of the various pairs in one single chamber and those of the other cylinders in a different chamber. The scavenging ports 6 of the cylinders are united in a single chamber 12.

The scavenging air from the pump 7 or other suitable member no matter how operated enters the scavenging ports 6 in the direction of the arrows 9 through the pipe 8; the combustion products pass out through exhaust ports 5 in the various cylinders through the pipe 10 and the exhaust box or boxes (not shown in the drawing). Each piston is connected either to the other pis-

ton in the same cylinder or to the corresponding piston of the other cylinder by means of a kinematic chain (forming the subject of another invention) in such manner as to obtain opposite movement of the said pistons. The said kinematic or other chain transmits the movement of the pistons, suitably transformed, to the driving wheels of the locomotive.

10 Although in the foregoing description only the type of engine illustrated has been described various modifications may nevertheless be made in practice for the solution of the problem and for obtaining other solutions all based however on the fundamental principles of the present invention. Thus for example the axes of the pair of horizontal cylinders could be arranged in such manner that they do not lie, as shown in the 15 drawing, in one vertical plane. Two or even more pairs of cylinders with horizontal axes could be disposed in any manner in relation to one another. The arrangement of the scavenging and exhaust ports could also be 20 modified.

Having now particularly described and ascertained the nature of our said invention and in what manner the same is to be performed, we declare that what we claim is:—

1. A locomotive fitted with an internal 30 combustion engine with horizontal cylinders, characterized by the fact that the engine consists of one or several couples of cylinders; two cylinders of each couple having parallel and distinct axes and each cylinder 35 having two pistons moving in opposite directions, and by the fact that the pistons placed on the same side of the two cylinders forming a couple are connected together by a member, one for each side, the said member 40 compelling the pistons to move in opposite directions.

2. A locomotive fitted with an internal combustion engine of the type indicated in claim 1, characterized by the fact that at 45 the end of their course the pistons in each cylinder of a couple are arranged to open, one the scavenging ports, and the other, the exhaust ports; while the two pistons of the other cylinder of the couple are at the end 50 of their phase of compression.

In testimony whereof we affix our signatures in presence of two witnesses,

ACHILLE MACCHIONI.
ENRICO HOCKE.
